REVERSIBLE SKIRT

Raphael Kamhi, Norwalk, Conn.

Application September 21, 1946, Serial No. 698,556

6 Claims. (Cl. 2—211)

1

This invention relates to a reversible skirt which can be worn by the wearer with either one side out or the other side out, the material having different patterns on the opposite faces thereof.

It is an object of the present invention to provide a side seam which can extend the full height of the skirt and which will appear alike on both faces regardless of which side is out.

It is another object of the invention to provide side seam portions of such type that they readily lend themselves to the connection of zipper elements at the top by which the skirt can be tightened about the wearer's hip.

It is another object of the invention to provide a flap on each side of the skirt which will extend over the zipper so that the zipper will appear neither from one side or the other.

It is another object of the invention to provide means in the strips whereby the zipper portions will be kept aligned even though they are disconnected.

According to the invention, the material is formed in two sections and sewed together at the opposite sides and then turned inside out to locate the overhang edges on the inside of the garment. In order to cover up these overhang edges two cover strips are sewed to the side of the garment and connected together to provide overhang edges opposing and aligned with the overhang portions of the main parts of the garment so that the skirt at the seam will have the same appearance regardless which side is out. At the top and one side of the skirt zipper strips are connected to separated portions of the main body parts of the garment. One of the side strips on the side of the garment having same provides for a flap adapted to extend over the zipper parts. On the opposite side of the garment a flap is fashioned into one of the main body parts.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the skirt turned to one side which has a figured surface.

Fig. 2 is a perspective view of the skirt turned to the other side.

Fig. 3 is a transverse cross-sectional view of the skirt taken along the line 3—3 of Fig. 1 and looking in the direction of the arrows thereof.

Fig. 4 is an enlarged detailed view of a portion of Fig. 3.

2

Fig. 5 is a partial horizontal cross-sectional view taken on the line 5—5 of Fig. 2.

Fig. 6 is an enlarged fragmentary view, in elevation, of the area of the skirt which houses the zipper.

Fig. 7 is an enlarged cross-sectional view of the zipper section taken along line 7—7 of Fig. 6 and looking in the direction of the arrows thereof and having flap portions to cover the zipper from both sides of the skirt.

Fig. 8 shows a detail enlarged cross sectional view of a modified placket closure comprising an inner and an outer slide fastener unit, each complete in itself.

Referring now to the figures, 10 represents a skirt having a top band or belt 11 and a bottom edge 12. This skirt can be turned to have either a figure side 13 out as shown in Fig. 1 or a plain side 14 out as shown in Fig. 2. The plain side may have a braided band 15 near its lower edge.

The skirt is made from material having different patterns on the opposite faces thereof. It comprises a main back strip 16 and a front strip 17 sewed together along the sides as indicated at 18 and 19. The sewing is done by first connecting the edges together and sewing through the two strips and then turning the garment so that from the outside only the seam lines 18 and 19 will appear on one side of the skirt. The overlap edges 21 are folded back out of the way and are covered by similarly sewed together cover strips 22 and 23 connected to the main strips at some distance from the seam line by stitching 24 and 25. The stitching of the strips 22 and 23 together are indicated at 26 and this stitching will appear, as a seam line when the skirt is turned with the inside out, the same as the seam lines 18 and 19 appear.

On the side of the skirt having the cover strips 22 and 23 the braided strip 15 is sewed near the lower edge of the skirt, Fig. 5. The braid will preferably cover the hem line of the folded in bottom edge of the skirt.

Near the top of the skirt zipper fasteners 28 and 29 are fashioned into the connected strips whereby to provide means for retaining the skirt over the hips of the wearer. Referring now particularly to Figs. 6 and 7, it will be noted that the zipper 28 is secured between a side strip 23 and the main skirt strip 17 as by stitching 31 which includes folded in edge 32 of the strip 23 and a facing strip 33 on the main body strip 17. This strip 33 is secured to the edge of the main body strip 17 at a point to the right of the stitching 31 as indicated at 34 and provides with the main strip 17 a double cover flap 35 for hiding the

zipper strips 28 and 29. On the other side of the zipper strips a similar arrangement for providing a cover flap 36 is provided on the side strip 22. A strip or facing 37 is sewed to the inner face of the side strip 22 and the facing and side strip sewed to the main strip 16 of the skirt body as indicated at 38.

In the band 11 of the skirt where the flaps of the zipper cross a button 41 of a double head variety is extended through buttonholes 42 upon the upper ends of these flaps. The button will hold the top band or belt together and at the same time keep undue strain from the zipper strips.

Referring to Fig. 6, a U-shaped spring 45 is provided at opposite sides of the zipper strips whereby to retard the downward movement of the zipper as it approaches the lower end of the strips. This U-shaped member is closed at its bottom end and is sewed into and between the main and cover strips of the skirt. The U-shaped member extends upwardly about half the length of the zipper. As the zipper is pulled down an indication will be made to the wearer that the end of the zipper strips is being approached. This U-shaped member will also serve to keep the zipper strips close together so that the return movement of the zipper element can be easily started and effected inasmuch as the strips are kept in alignment with each other. As the skirt is drawn from the wearer the spring will give sufficiently so as not to hinder or make the removal of the skirt any the less difficult.

Fig. 8 shows a modified construction of the placket closure. To the skirt body section 17 a strip 47 is secured by the stitching 48 and this strip is provided with a slide fastener row which cooperates with the slide fastener row of the strip 49, which is secured by the stitching 52 to the skirt body section 16. The skirt body section 17 is provided with an edge strip 46, and the adjacent engaged edges of this strip and of the section 17 are folded inwardly and stitched together. The slide fasteners 48^a and 48^b form a complete closure for the adjacent edges of the body sections 16 and 17, and the edge of the outer body section 17 overlaps the adjacent edge of the body section 16 to fully conceal the slide fastener closure.

The covering flap strip 23 is provided with a strip of slide fasteners 53 secured by stitching, and the covering flap 22 is provided with a strip of cooperating slide fasteners 55 secured by the stitching 56 thereto. An inner facing strip 54 is stitched to the inwardly folded edge portion of the cover flap 22, and overlaps the slide fasteners of the strips 53 and 55 to fully conceal the same.

It should now be apparent that there has been provided a skirt which will have the same appearance so far as the seam lines are concerned no matter which side of the skirt is turned out. It should be further apparent that there has been worked into one side construction near the top of the skirt and formed from the covering strips and the main strip material, cover flaps for the zippers which will cover the same from both sides of the skirt, one flap for one side and the other flap for the other side.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. A reversible skirt comprising double faced main strips having their adjacent edges turned in and sewed together so that only seam lines will appear from the outside of the skirt, cover strips within the skirt having their adjacent edges turned out and sewed together and disposed over said turned edges to show a single seam line on the inside of the skirt, said cover strips being connected to the main strips on opposite sides of their seam lines and removed from the seam lines whereby said skirt whether turned in or out will show a similar seam line, the main strips being separated near the top of the skirt and at one side thereof, the cover strips being similarly separated in the same location of the skirt, and zipper strips respectively connected between the main and cover strips and adapted to be joined with one another, one of said cover strips having a facing thereon and extending laterally over one face of the zipper strips, and portions of one of the main strips having a facing and extending over the other face of the zipper strips, cover strips, facings, main strips, and zipper strips on opposite sides of said zipper strips being sewed together by separate lines of stitching.

2. A reversible skirt comprising double faced main strips having their adjacent edges turned in and sewed together so that only seam lines will appear from the outside of the skirt, cover strips within the skirt having their adjacent edges turned out and sewed together and disposed over said turned edges to show a single seam line on the inside of the skirt, said cover strips being connected to the main strips on opposite sides of their seam lines and removed from the seam lines whereby said skirt whether turned in or out will show a similar seam line, the main strips being separated near the top of the skirt and at one side thereof, the cover strips being similarly separated in the same location of the skirt, and zipper strips respectively connected between the main and cover strips and adapted to be joined with one another, one of said cover strips extending laterally over one face of the zipper strips and portions of one of the main strips extending over the other face of the zipper strips, cover strips, main strips and zipper strips on opposite sides of said zipper strips being sewed together by separate lines of stitching.

3. A reversible skirt comprising double faced main strips having their adjacent edges turned in and sewed together so that only seam lines will appear from the outside of the skirt, cover strips within the skirt having their adjacent edges turned out and sewed together and disposed over said turned edges to show a single seam line on the inside of the skirt, said cover strips being connected to the main strips on opposite sides of their seam lines and removed from the seam lines whereby said skirt whether turned in or out will show a similar seam line, the main strips being separated near the top of the skirt and at one side thereof, the cover strips being similarly separated in the same location of the skirt, and zipper strips respectively connected between the main and cover strips and adapted to be joined with one another, one of said cover strips extending laterally over one face of the zipper strips, and portions of one of the main strips extending over the other face of the zipper strips, cover strips, main strips and zipper strips on opposite sides of said zipper strips being sewed together by separate lines of stitching, said skirt having a top

band or belt with buttonholes in its ends, and a button joining the belt ends together.

4. A reversible skirt comprising double faced main strips having their adjacent edges turned in and sewed together so that only seam lines will appear from the outside of the skirt, cover strips within the skirt having their adjacent edges turned out and sewed together and disposed over said turned edges to show a single seam line on the inside of the skirt, said cover strips being connected to the main strips on opposite sides of their seam lines and removed from the seam lines whereby said skirt whether turned in or out will show a similar seam line, the main strips being separated near the top of the skirt and at one side thereof, the cover strips being similarly separated in the same location of the skirt, and zipper strips respectively connected between the main and cover strips and adapted to be joined with one another, a U-shaped spring member disposed between the main and cover strips and fashioned to surround the lower end of the zipper strip whereby to retain the zipper strip in closed relationship after they have been disengaged by the zipper element and to serve as an indication to the wearer that the end of the zipper action is being approached.

5. A reversible skirt comprising double faced main strips having their adjacent edges turned in and sewed together so that only seam lines will appear from the outside of the skirt, cover strips within the skirt having their adjacent edges turned out and sewed together and disposed over said turned edges to show a single seam line on the inside of the skirt, said cover strips being connected to the main strips on opposite sides of their seam lines and removed from the seam lines whereby said skirt whether turned in or out will show a similar seam line, two sets of zippers extending side-by-side at the upper portion of the skirt, one set of zippers being disposed between the main strips and the other set of zippers being disposed between the cover strips connected to the main strip to hide them from view when the skirt is being worn with the main strip seam on the outside, one of said cover strips having a facing strip secured to its edge and folded back to be secured with a zipper strip to the cover strip, said cover strip and facing strip adapted to extend over the set of zippers disposed between the cover strips to hide them from view.

6. A reversible skirt comprising double faced main strips having their adjacent edges turned
